CLAIM

The ornamental design for a chair shell, as shown and described.

DESCRIPTION

This application is related to the following applications: U.S. design patent application Ser. No. 29/304431, filed on Feb. , 2008, the disclosures of which are incorporated herein by reference.

FIG. 1 is a perspective view of the chair shell showing our new design;

FIG. 2 is a front elevational view thereof;

FIG. 3 is a left side elevational view thereof, the right side elevational view being a mirror image;

FIG. 4 is a rear elevational view thereof;

FIG. 5 is a top plan view thereof; and,

FIG. 6 is a bottom plan view thereof.

The broken line showing of chair legs is included for the purpose of illustrating environmental structure and forms no part of the claimed design.
